(74) Attorney, Agent, or Firm — Hudak, Shunk & Farine
Co. LPA(57) CLAIM

The ornamental design for a handle, as shown and described.

DESCRIPTION

FIG. 1 is a top front right perspective view of a handle;
FIG. 2 is a top view thereof;
FIG. 3 is a bottom view thereof;
FIG. 4 is a right side view thereof;
FIG. 5 is a left side view thereof;
FIG. 6 is a front view thereof; and,
FIG. 7 is a rear view thereof.
The broken lines in the drawings depict portions of the handle that form no part of the claim.
